United States Patent Office

Des. 180,429
Patented June 4, 1957

180,429

MEMORANDUM SLATE OR SIMILAR ARTICLE

Dorothy V. Taylor, Wilmington, Del., assignor to
Eric Philip Company, Wilmington, Del.

Application December 6, 1955, Serial No. 39,176

Term of patent 3½ years

(Cl. D25—1)

The single figure is a plan view of a memorandum slate or similar article, showing my new design.

I claim:

The ornamental design for a memorandum slate or similar article, substantially as shown.
